BOTTLE HANDLING DEVICE

Elmer Johnson, Middlesboro, Ky.

Application May 22, 1951, Serial No. 227,544

13 Claims. (Cl. 294—87.24)

1

This invention relates to improvements in bottle lifts of the character used for lifting empty beverage bottles from cases into the soaker of a bottling plant.

Beverage bottles usually are brought to the bottling plant in cases in which they are supported in rows and from which cases they must be lifted or separated to transfer them to the bottle soaker. This lifting of the bottles out of the cases is a hand operation involving the manual grasping and removal of the bottles from the cases.

Many different forms of bottle handling devices have been proposed heretofore for use in lifting the bottles out of the cases to the soaker, but for the most part these have been unsatisfactory. Those which are made of metal wear in use and are often heavy to lift. The use of springs in the gripping mechanism has been unsatisfactory because of corrosion and ineffective gripping of the bottles. Complex structures often are involved, which have rendered the lifts expensive to build and ineffective in service. Many of these have resulted in breakage of the glass bottles, which is a serious problem in bottling plants.

One object of this invention is to improve the construction of bottle lifts for this purpose, to enable these to be manufactured inexpensively, without complex grasping mechanism, to be light in weight, and free of glass breakage to a maximum degree.

Another object of the invention is to provide for the construction of a bottle lift with a wedge lock that requires no grip in lifting the bottles and no springs for movement of the operating part, and which will effectively and simply grasp the bottles for a lifting action with few moving parts.

These objects may be accomplished, according to certain embodiments of the invention, by providing a pair of coating bars, relatively movable, to embrace the necks of a row of bottles that are to be lifted out of the case to the soaker. These bars are relatively moved to a clamping relation with the bottles by wedging means actuated without springs or an excess number of moving parts. It is preferred that the lift be provided with two pairs of gripping devices, one on each side, so as to engage and lift two rows of bottles at the same time. Both lift devices may be actuated by a single wedging means interposed therebetween that is simple and effective and which functions merely by the action of the operator in lifting the device for engaging the lifting means with the bottles.

This embodiment is illustrated in the accompanying drawings in which:

2

Fig. 1 is a perspective view of the device, shown in its supporting relation to the bottles;

Fig. 2 is a side elevation thereof, with parts broken away and in section;

Fig. 3 is a cross-section therethrough on the line 3—3 in Fig. 2, showing the lifting means in its disengaged position;

Fig. 4 is a similar view showing the lifting means in engaged or lifting position;

Fig. 5 is a cross-section therethrough on the line 5—5 in Fig. 2; and

Fig. 6 is a cross-section through the mid portion of the lifting unit showing a modification of the construction.

10 15 The bottle lift illustrated as an embodiment of the invention in Figs. 1 to 5 comprises upright end plates 1, spaced apart at suitable distances according to the number of bottles to be handled by the lift. These plates 1 are connected together at the top by a hand rail or spacer 2, interposed therebetween and held in secured relation with respect thereto, not only for spacing the end plates apart, but also for securing the latter in fixed relation to each other. In the embodiment illustrated the hand rail or spacer 2 has reduced ends fitted into sockets in the inner faces of the end plates 1 and are secured thereto by adhesive or by screw fastenings 3, or other suitable fastening means.

20 25 Interposed between the facing sides of the end plates 1, adjacent the lower edges thereof, are side bars 4, secured in fixed relation to the end plates 1. In the embodiment illustrated sockets 5 are provided in the inner faces of the end plates and receive therein the extreme ends of the side bars 4, within which sockets these ends are secured by adhesive or other suitable fastening means. In the form shown, these side bars 4 are elongated transversely in cross-section, as viewed in Figs. 3 to 5, and are arranged in converging oblique positions with respect to the upright longitudinal plane through the lift whereby the side bars tend to guide the necks of the bottles into the lift for supporting the bottles thereby.

30 35 40 45 Arranged in cooperating relation with the side bars 4, and spaced inwardly therefrom, are lifting bars or gates 6, which latter extend lengthwise of the lift device between the end plates 1. The lifting bars 6 are mounted on the end plates 1, for swinging movement toward and from the adjacent side bars 4, so as to cooperate with the latter in engaging and lifting rows of bottles as shown in Figs. 1 and 4. Each of the lifting bars 6 has a trunnion 7 on each end thereof adjacent the lower edge, which trunnions are journalled in sockets 8 in the respective end plates 1, so as

to permit of swinging movement of the lifting bars 6 transversely with respect to the side bars 4. This swinging movement is limited, however, by trunnions 9 on the opposite ends of each lifting bar 6, adjacent the upper edge thereof. The trunnions 9 are guided in grooves 10 formed in the inner faces of the end plates 1 and elongated on arcs substantially concentric with the sockets 8, as will be apparent from Figs. 3 to 5. Each of the lifting bars 6 is shown as having openings 11 therethrough, receiving wedges 12 interposed between the pair of lifting bars 6 in the embodiment illustrated, whereby the lifting of the wedges 12 will cause a spreading action of the upper edge portions of the lifting bars 6, away 15 from each other, from the position shown in Fig. 3 to the position shown in Fig. 4. A pair of wedges 12 is provided, preferably spaced lengthwise of the bottle lift, as shown in Fig. 2, although the number used may be varied as desired. 20

The wedges 12 are mounted on and secured to upright pins 13, that extend downward between the lifting bars 6 and are guided between the lower edges of the latter so as to maintain the wedges in proper relation with respect to the lifting bars. The pins 13 are secured at their upper ends to a handle or bail 14 that extends lengthwise of the lift, as shown in Fig. 2, and is slidably mounted with respect to the end plates 1. In the form illustrated, the handle or bail 30 14 has reduced opposite ends, received in vertical slots 15 formed in the end plates 1, for guiding the handle or bail vertically with respect thereto, and allowing freedom of lowering movement by gravity when the handle or bail is released.

It is preferred that the lift be constructed entirely of wood throughout, not only because this reduces appreciably the weight of the lift, but also because I have found that it serves to reduce substantially the amount of breakage of 40 bottles, stopping it almost entirely. Moreover, it reduces appreciably the wearing of the lift as compared with the metal lifts used heretofore.

The end plates 1 are formed of maple, while all the other parts of the lift are formed of dogwood. These two woods work most effectively and accomplish the best results of light weight, sturdy construction and effective operation. However, it is recognized that other materials may be used in place thereof, and other woods may be substituted in place thereof, if desired, in forming the parts of the device. 45

It will be recognized that the lift may be handled by the operator in a simple and effective manner, to grasp any desired number of bottles in the crate. It will be manipulated by the operator picking up the lift by the hand rail 2 and handle 14, and while so holding it, principally with the hand rail 2, it will be fitted over the rows of bottles in the crate which will be directed between the bars 4 and 6 by the converging relation of the latter as viewed in Fig. 3. After the bars have been lowered over the necks of the bottles, the operator merely grasps or lifts with the fingers the handle or bail 14, which lifting action will raise the wedges 12 with respect to the upper edge portions of the lifting bars 6, causing a locking of the latter with respect to each other to clamp the necks of the bottles between the upper edge portions of the coating bars 4 and 6. The crowning rings usually provided on the necks of the bottles will be engaged above the bars 4 and 6, as viewed in Figs. 1 and 4 of the drawings, which will serve 70 75

to support the bottles by the lift as the latter is lifted from the case to the soaker.

The bottles may be released readily and quickly without any springs or other parts which would rust or break, merely by releasing the handle or bail 14. The weight of the latter and of the wedges 12 will allow these to drop to the positions shown in Fig. 3, which will be facilitated by the pressure against the lifting bars 6, so as to release the bottles readily. This forms an effective wedge lock which will engage and lift the bottles readily, and yet which can be released without difficulty and ensures an effective release of the bottles without striking the bottoms on the machine, which thereby reduces breakage appreciably.

The size of the lift may be varied according to the number of bottles to be handled thereby. It is shown in Fig. 1 as applied to eight bottles, but if it is desired to handle twelve bottles at each operation, this may be provided readily by extending the length of the parts between the end plates 1. In that event a brace may be used between the side bars 4, as illustrated at 16, in Fig. 6, to strengthen the latter. Otherwise the construction is the same as set forth above, and functions in the same manner.

While the invention has been illustrated and described in certain embodiments, it is recognized that variations and changes may be made therein without departing from the invention as claimed. In place of handling two rows of bottles, the lift may be so made as to handle only one row of bottles by using only a single set of coating bars, if desired.

I claim:

1. A bottle lift comprising a pair of upright end structures, a pair of lifting bars extending between the end structures in position to receive bottles therebetween for clamping relation thereto, means for mounting the lifting bars on the end structures for swinging movement under the force of gravity of one of said bars toward the other coating bar in clamping relation with the bottles, such swinging movement being about an axis substantially parallel to the longitudinal axis of said one of said bars, means for applying a wedging action to said swinging bar to lock it in clamping position against said bottles, and means applying a force on said swinging bar to move the top of said bar away from said coating bar.

2. A bottle lift comprising a pair of upright end structures, a pair of lifting bars extending between the end structures in position to receive bottles therebetween for clamping relation thereto, means for mounting the lifting bars on the end structures for swinging movement of one of said bars toward and from the other coating bar in clamping relation with the bottles, such swinging movement being about an axis substantially parallel to the longitudinal axis of said one of said bars, a wedge in bearing relation with the movable bar for locking said swinging bar in its clamping relation with said bottles, and a handle connected with the wedge.

3. A bottle lift comprising a pair of upright end structures, a side bar extending between the end structures and fixed thereto, a lifting bar extending between the end structures and spaced from the side bar to receive bottles therebetween and coating with the side bar in clamping engagement with the bottles, and means journaling the lifting bar on the end structures for swinging movement about an axis substantially parallel

to the longitudinal axis of said lifting bar under the force of gravity toward the side bar, and means supported on said end structures for moving said lifting bar away from said side bar.

4. A bottle lift comprising a pair of upright end structures, a side bar extending between the end structures and fixed thereto, a lifting bar extending between the end structures and spaced from the side bar to receive bottles therebetween and coacting with the side bar in clamping engagement with the bottles, means journaling the lifting bar on the end structures for swinging movement about an axis substantially parallel to the longitudinal axis of said lifting bar toward and from the side bar, and lifting means movably connected with the end structures for locking the lifting bar in its clamping relation with the bottles therebetween.

5. A bottle lift comprising upright end structures, a side bar extending between the end structures and fixed thereto, a swingable lifting bar extending between the end structures and spaced from the side bar to receive bottles therebetween and coacting with the side bar in clamping engagement with the bottles, means journaling the lifting bar on the end structures for swinging movement about an axis substantially parallel to the longitudinal axis of said lifting bar toward and from the side bar, said side bar and lifting bar being elongated transversely in cross-section and arranged in oblique positions inclined toward each other for guiding the bottles therebetween.

6. A bottle lift comprising a pair of upright end plates having a recess formed in each of their respective opposed sides, a pair of spaced side bars extending between the end plates and fixed thereto, a pair of lifting bars extending between the end plates in side-by-side relation, each of the lifting bars being spaced from an adjacent side bar in position to coact therewith and receive bottles therebetween, trunnions on the lifting bars journaled on the end plates and mounting the lifting bars thereon for swinging movement of the lifting bars in opposite directions about axes substantially parallel to the longitudinal axes of said lifting bars, said lifting bars normally swinging toward said side bars in the absence of bottles therebetween, wedges interposed between the lifting bars, a handle slidably mounted in said recesses in the end plates and extending therebetween, and pins connected with the wedges and the handle for moving the wedges relative to the lifting bars upon lifting movement of the handle.

7. A bottle lift comprising a pair of upright end plates having a recess formed in each of their respective opposed sides, a pair of spaced side bars extending between the end plates and affixed thereto, a pair of lifting bars extending between the end plates in side-by-side relation, each of the lifting bars being spaced from an adjacent side bar in position to coact therewith and receive bottles therebetween, trunnions on the lifting bars journaled on the end plates and mounting the lifting bars thereon for swinging movement of the lifting bars in opposite directions about axes substantially parallel to the longitudinal axes of said lifting bars, said side bars and lifting bars being elongated transversely in cross section and arranged in oblique positions inclined toward each other for guiding the bottles therebetween, said lifting bars being mounted for swinging movement automatically toward said side bars in the absence of bottles therebe-

tween, wedges interposed between the lifting bars in bearing relation with respect thereto, a handle slidably mounted in said recesses formed in each of the end plates and extending therebetween, and means connecting the wedges with the handle, whereby upon lifting movement of the wedges, said lifting bars are locked in position against said bottles, and upon downward movement of the wedges said wedges force said lifting bars away from said bottles.

8. A bottle lift comprising a pair of upright end plates having substantially rectangular and elongated arcuately-shaped recesses formed in their respective opposed sides, a pair of spaced side bars extending between the end plates and fixed thereto, a pair of lifting bars extending between the end plates in side-by-side relation, each of the lifting bars being spaced from an adjacent side bar in position to coact therewith and receive bottles therebetween, a trunnion extending from each end of each lifting bar and journaled on the respective end plates and mounting the lifting bars thereon for swinging movement of the lifting bars in opposite directions about axes substantially parallel to the longitudinal axes of said lifting bars, a second trunnion extending from each end of each lifting bar, said second trunnion being positioned within said arcuate recesses for guiding and sliding movement relative thereto, said side bars and lifting bars being elongated transversely in cross section and arranged in oblique positions inclined toward each other for guiding the bottles therebetween, said lifting bars automatically swinging toward the side bars in the absence of bottles therebetween, wedges interposed between the lifting bars, a handle slidably mounted in said rectangular recesses in each of the end plates and extending therebetween, and means connecting the wedges and the handle for moving the wedges to engage and lock the lifting bars against swinging movement away from said side bars upon lifting movement of the handle.

9. A bottle lift comprising a side rail and a gate spaced apart to receive a bottle therebetween, means mounting the side rail laterally inclined toward the gate, means pivotally supporting the gate for swinging movement about an axis substantially parallel to the longitudinal axis of said gate toward and from the side rail to secure the bottle therebetween in one position, and means for limiting the swinging movement of the gate away from the side rail to a position inclined toward the side rail.

10. A bottle lift comprising a side rail and a gate spaced apart to receive a bottle therebetween, means mounting the side rail laterally inclined toward the gate, means pivotally supporting the gate for swinging movement about an axis substantially parallel to the longitudinal axis of said gate toward and from the side rail to secure the bottle therebetween in one position, means for limiting the swinging movement of the gate away from the side rail to a position inclined toward the side rail, and means for locking the gate in the bottle securing position.

11. A bottle lift comprising a pair of spaced end members, a side bar fixed at opposite ends to said end members, a lifting bar extending between the end members and spaced laterally from the side bar, said lifting bar being elongated transversely of the length thereof in an upward direction relative to the lift, means pivotally supporting the lifting bar on the end members in an oblique position inclined toward the side

bar and for swinging movement about an axis substantially parallel to the longitudinal axis of said lifting bar toward and from the side bar, said side and lifting bars being positioned to receive a bottle neck therebetween and the lifting bar being mounted for swinging movement away from the side bar upon insertion of the bottle neck therebetween and for swinging movement toward the side bar to hold the bottle neck therebetween, and a wedge member in position for locking the lifting bar against swinging movement to hold the bottle neck retained between the bars. 5

12. A bottle lift comprising a pair of spaced end members, two pairs of clamping devices extending between the end members in side-by-side relation, each of the clamping devices comprising a side bar having its ends fixed to the end members, a lifting bar spaced laterally from the side bar and inwardly therefrom, each of said bars being elongated transversely of the length thereof in an upward direction relative to the lift, means pivotally supporting the lifting bar on the end members in upwardly inclined relation laterally toward the adjacent side bar 15 and for swinging movement about an axis substantially parallel to the longitudinal axis of said lifting bar toward and from the latter, said side and lifting bars being positioned to receive a bottle neck therebetween and to clamp the 20 bottle neck by the swinging movement of the 25

lifting bar toward the side bar, and a wedging device interposed between the lifting bars of the clamping devices for clamping said lifting bars in holding relation with the bottle necks therein. 10

13. A bottle lift comprising a pair of spaced end members, a side bar fixed at opposite ends to said end members, a lifting bar extending between the end members and spaced laterally from the side bar, each of said bars being elongated transversely of the length thereof in an upward direction relative to the lift, said lifting bar having trunnions at opposite ends thereof at its lower edge journaled in the end members and having trunnions at opposite ends thereof at its upper edge extending into the end members, said end members having grooves therein receiving the last-mentioned trunnions for lateral swinging movement of the lifting bar toward and from the side bar about the axis of said first-mentioned trunnions, and means for locking the lifting bar in inwardly clamping relation relative to the side bar. 20
